Des. 212,636
Patented Nov. 5, 1968

212,636

HOUSING FOR A ROTARY LAWMOWER

Viktor Schreckengost, Cleveland Heights, Ohio, assignor
to The Murray Ohio Manufacturing Co., Nashville,
Tenn., a corporation of Ohio

Filed Jan. 22, 1968, Ser. No. 10,264

Term of patent 14 years

(Cl. D40—1)

Fig. 1

Fig. 2

Fig. 3

Fig. 4

FIG. 5

FIG. 6

FIGURE 1 is a top plan view of a housing for a rotary lawnmower;

FIGURE 2 is a side elevational view thereof;

FIGURE 3 is a bottom plan view thereof;

FIGURE 4 is an elevational view of the side opposite that illustrated in FIGURE 2;

FIGURE 5 is a front elevational view; and

FIGURE 6 is a rear elevational view.

I claim:

The ornamental design for a housing for a rotary lawnmower, substantially as shown.
